UNITED STATES PATENT OFFICE.

JOSEPH W. BARNA, OF CHICAGO, ILLINOIS.

SHOE-FASTENER.

No. 884,454.

Specification of Letters Patent. Patented April 14, 1908.

Application filed April 19, 1907. Serial No. 369,048.

To all whom it may concern:

Be it known that I, JOSEPH W. BARNA, a citizen of the United States, residing at Chicago, in the county of Cook and State of Illinois, have invented certain new and useful Improvements in Shoe-Fasteners, of which the following is a specification, reference being had therein to the accompanying drawing.

10 My invention relates to new and useful improvements in shoe-fasteners designed to be used to hold together the edges of shoe-uppers during the progress of the manufacture of shoes.

15 The invention consists of the organizations and arrangements of parts hereinafter described and then pointed out in the appended claims.

20 In the accompanying drawings—Figure 1 is a perspective view of a shoe showing my fastener in position to hold the edges of the shoe-upper together and to retain the tongue; Fig. 2 is a plan view of the fastener in open position; Fig. 3 is a plan view of the 25 fastener in closed position; and Fig. 4 is a transverse section of the fastener on the line 4—4 of Fig. 3.

25 The fastener is made of sheet metal, preferably of a resilient character, and comprises 30 two side members 6 and 7 integrally joined at one end by a web 8, the parts being of any suitable widths. As is clearly shown in Fig. 2, these side members normally are divergently disposed and tend to separate.

35 The side members are provided with hooks 35 to be inserted into the eyelets of the shoe-uppers; in the present case these hooks are not formed directly upon the side members, but each side member is provided with a 40 wing 9 having tongues forming hooks. The side members and wings are formed to conform to the arch of the instep, and the ends of the side members are bent downwardly as at 10 where they join the wings so that the 45 latter lie in a plane somewhat below their associated side members, all as clearly shown in Fig. 4.

The tongues 11 project laterally from the wings, and are bent downwardly and then 50 curved inwardly to form hooks 12, and are then curved outwardly and downwardly to provide laterally extending portions 13. While each wing is shown as having but two tongues it is of course to be understood that 55 more may be provided and, as in the present instance, these hooks together with the hooks

14 on the web are disposed so as to engage the first, third and fifth pairs of eyelets from the bottom of the shoe-upper, as shown in Fig. 1. The hooks on the web are formed 60 similarly to the hooks 12.

The fastener being made of resilient metal the side members are drawn together and held in their closed position and prevented from springing apart by means of metal 65 clip 15, the ends of which are bent to form suitable hooks 16 to loosely engage the side members and slide thereon; the clip may also be provided with a suitable downwardly projecting lug 17 on its under side. Each 70 wing is joined to its associated side member at the free end of the latter, and extends substantially parallel therewith at the side thereof being suitably separated therefrom to provide a passage for the free movement 75 of the clip 15 in closing the side members, and being below the side pieces and resting on the shoe-upper they hold the side-pieces at sufficient elevation to provide space for the free movement of the clip and prevent 80 the clip from scraping the upper.

The wings provide a plurality of hooks for each side member while they also leave the side members free of all obstructions for substantially their entire length, whereby 85 the clips may engage directly with these members and slide freely from end to end thereof. The resiliency of the fastener resides wholly within the side members, and the clip when at the lower end as shown in 90 Fig. 2 does not exert any closing tendency.

The lug 17 is designed to press against the tongue of the shoe while the clip is moved back and forth and thus prevent the edges of the clip from scraping against the shoe- 95 upper. The wings being in a plane lower than the side members and adapted to rest upon the shoe-upper sufficient space is allowed to also prevent the clip from scraping the uppers.

100 The fastener is preferably provided with means to engage the tongue of the associated shoe, and this engaging means may be of any suitable form. In the form shown one of the side members is provided at its upper end 105 with an eye in an upstanding flange 18, and the other member is provided with a projection or lug 19 adapted to pass into the eye when the side members are closed as shown in Figs. 1 and 4. If desired a second projection may be employed either above or below the flange, as shown in dotted lines in 110

Figs. 2 and 3. When the side members are to be closed the stock of the tongue of the shoe is brought between the coöperating parts so that the lug pushes the stock 5 through the hole or eye and around the flange and holds it in place as shown in Fig. 1. This is especially desirable when lasting Blucher 10 shoes, as it prevents the tongue from being drawn down when the upper is pulled over the last; the ankle-seam in these shoes does not extend into the vamp and so when the latter is pulled over the last the tongue is dragged down the center and the shape of the shoe is distorted. The coöperating 15 means hold the stock of the tongue in place and prevents this distortion.

The application of my device may be briefly described as follows. The last having been placed within the shoe-upper the 20 hooks are inserted into the proper eyelets, the tongue of the shoe is raised to be caught by the lug 19, and the side members are then drawn together and held in locked position by the clip. To remove the fastener the 25 clip is slid to its open position near or against the web and the side members which have been held together under tension spring apart and resume their normal or divergently disposed position, when the hooks may 30 then be readily removed from the eyelets of the shoe-upper.

Having described my invention what I claim as new and desire to secure by Letters Patent of the United States, is—

35 1. A metal shoe fastener comprising a pair of divergently disposed resilient side members, a web connecting the side members at one end, a parallel wing connected to each side member at its free end, eyelet engaging 40 hooks on the wings and the web, and a clip sliding on the said members.

2. A shoe-fastener comprising a pair of divergently disposed spring side members, a web connecting the side members, a parallel wing connected to the free end of each side 45 member and below the same, hooks on the web and wings, and a clip sliding on the side members.

3. A shoe-fastener made from a single blank of sheet metal comprising a pair of 50 resilient side members, a web connecting the side members, wings on the free ends of the side members, the wings and web provided with eyelet hooks, a clip sliding on the side members and having a lug depending below 55 the side members to engage the tongue of a shoe.

4. A fastener for shoe-uppers consisting of a pair of connected side-members having eyelet-engaging means, means to retain the 60 members in closed position, and means on the members to retain the tongue of the shoe.

5. A fastener for shoe-uppers consisting of a pair of connected side-members having eyelet-engaging means, means to retain the 65 members in closed position, and coöperating parts on the members to retain the tongue of the shoe.

6. A fastener for the shoe-uppers consisting of a pair of connected side-members having eyelet engaging means, means to retain the 70 members in closed position, an eye on one member and a coöperating lug on the other member to engage the tongue of the shoe when the members are closed. 75

In testimony whereof I affix my signature in presence of two witnesses.

JOSEPH W. BARNA.
